[57] CLAIM

The ornamental design for an universal bed for flat bed hand carts, as shown and described.

DESCRIPTION

FIG. 1 is a top plan view of a universal bed for flat bed hand carts showing our new design;

FIG. 2 is a bottom plan view thereof;

FIG. 3 is a rear elevational view thereof;

FIG. 4 is a left side elevational view thereof, the right side being a mirror image;

FIG. 5 is a front elevational view thereof;

FIG. 6 is a top plan view of a second embodiment of the universal bed for flat bed hand carts;

FIG. 7 is a bottom plan view of FIG. 6;

FIG. 8 is a left side perspective of FIG. 6, the right side being a mirror image;

FIG. 9 is a rear view of FIG. 6;

FIG. 10 is a front elevational view of FIG. 5; and,

FIG. 11 is a left side view of FIG. 6, the right side being a mirror image.
